Inventor

William W. Kirchner

United States Patent Office.

WILLIAM M. KIRCHNER, OF PITTSBURG, PENNSYLVANIA.

Design No. 4,754, dated April 4, 1871.

DESIGN FOR A JELLY-GLASS.

The Schedule referred to in these Letters Patent and making part of the same.

To all whom it may concern:

Be it known that I, WILLIAM M. KIRCHNER, of Pittsburgh, in the county of Allegheny and State of Pennsylvania, have invented a new and useful Improved Design for Jelly-Glass; and I do hereby declare the following to be a full, clear, and exact description thereof, reference being had to the accompanying drawings forming part of this specification, in which—

Figure 1 is a perspective view of a jelly-glass made after my improved design; and

Figure 2 is a like view of the same with the cap.

My design consists in a jelly-glass having a triangularly-shaped mouth and a triangularly-shaped cap or cover with flanged edges to fit onto the mouth.

Around the mouth of the glass *a* is a bead, *b*, either continuous and unbroken or broken at intervals.

The cap *c* is of like shape so as to fit onto the mouth of the glass *a*.

The edges of two sides of the cap *c* are folded down

and under so as to fit around the bead *b*, as at *c'*, and the edge of the other side of the cap is bent down a little so as to require but a slight pressure to spring it over the bead, as at *c''*.

The cap *c* slides onto the mouth of the glass, the folded sides *c'* fitting against the bead *b* on two sides, and the side *c''* slipping over the bead on the third side.

What I claim as my improved design, and desire to secure by Letters Patent, is—

1. A design for a jelly-glass, having a triangularly-shaped mouth, as described and shown.

2. A design for a triangularly-shaped cap for a triangularly-shaped jelly-glass, as described and shown.

In testimony whereof I, the said WILLIAM M. KIRCHNER, have hereunto set my hand.

WILLIAM M. KIRCHNER.
